UNITED STATES PATENT OFFICE.

FRIEDRICH PAUL PRIEM, OF HEIDENHEIM-ON-THE-BRENZ, GERMANY, ASSIGNOR, BY MESNE ASSIGNMENTS, TO THE CHEMICAL FOUNDATION, INC., A CORPORATION OF DELAWARE.

METHOD FOR NARROWING FIBER STRIPS IN MANUFACTURING ROVINGS FROM PAPER PULP AND SIMILAR FIBROUS MATERIAL.

Application filed July 7, 1919. Serial No. 309,149.

To all whom it may concern:

Be it known that I, FRIEDRICH PAUL PRIEM, citizen subject of Heidenheim, residing at Heidenheim-on-the-Brenz, Germany, have invented certain new and useful Improvement in Methods for Narrowing Fiber Strips in Manufacturing Rovings from Paper Pulp and Similar Fibrous Material, for which I have filed applications in Germany, Mar. 14, 1918; Denmark, Nov. 5, 1918; Finland, May 29, 1918; Austria, Nov. 2, 1918; Holland, Nov. 9, 1918; Hungary, Nov. 5, 1918; Sweden, Oct. 28, 1918; Norway, Nov. 16, 1918; Switzerland, Oct. 26, 1918; Belgium, Dec. 2, 1918; Luxembourg, Oct. 30, 1918, and of which the following is a specification.

In the manufacture of rovings from paper pulp or similar fibrous material narrow strips are produced on a paper web or paper cylinder machine, which strips were rounded or narrowed by a special rubbing apparatus. The latter consists of two india rubber endless belts or two rubber mantles placed on rolls and operated so as to be subjected to a lateral to and fro motion, thereby rounding the strips carried between them. Rubber, however, is an article, which is costly and frequently difficult to obtain. A suitable surrogate for rubber has not yet been found. On the other hand for preparing paper pulp strips for spinning or even for reeling to spools it is of importance that the strips be narrowed or rounded. According to the present invention the heretofore known rubbing machines are replaced by folding devices, through which the strips produced in the paper machines are led so as to be folded longitudinally. The folding apparatus may either be so constructed that the strips are folded once or twice or are folded into a tubular shape. The invention, therefore, has for its main object a method for narrowing or rounding strips such as are produced in the manufacture of rovings from paper pulp or similar material. The method consists therein that the strips coming from the strip producing machine are folded longitudinally while still in a wet state and thereupon

reeled up in any convenient manner to form spools or the like.

In the drawing an apparatus is shown constructed according to the present invention.

Fig. 1 is a diagrammatical elevation of the machine and

Fig. 2 is a similar view of a part of the machine drawn to a larger scale.

Fig. 3 is an end view of that part of the machine shown in Fig. 2.

Figs. 4^a to 4^c are sections drawn to the lines A—A, B—B, C—C, D—D, E—E, F—F, G—G of Fig. 3.

Fig. 5 is an elevation of part of the machine in a modified construction.

In the construction shown by way of example four folding devices are used for narrowing the strips in longitudinal direction. The strips produced by the machine are led to the folding apparatus c', c², c³, c⁴ and the narrowed strips are then led to the reeling devices h', h², h³, h⁴ in known manner. In the construction shown the paper strips are led through the folding devices by an endless band d. The folding funnel c is about the double breadth at its upper end of the belt d, that is to say it has about the breadth of the strip. At the lower or delivery end the folding funnel has the breadth of the strip when folded, thus in the construction shown when doubled up. The manner in which the strip is folded, will be clearly understood by examining the Figs. 3 and 4^a to 4^c.

It may here be said that it is not necessary to make use of the large delivery or distributing roller b, since it is also possible to lead the strips away to the folding apparatus from the guiding roll f, Fig. 5.

The folding apparatus may be combined with the reeling device. Such a combination is shown by way of example in Fig. 5, in which the endless belt at its lower end, where it passes the lower roller e carries the spool g guided in any suitable manner.

I claim:

1. Method for narrowing or rounding fiber strips in manufacturing rovings from paper pulp or similar fibrous material con-

sisting therein that the strips coming from the strip producing machine are folded longitudinally while still in a wet state and thereupon reeled up in any convenient manner to form spools and the like.

2. A method of manufacturing rovings from paper pulp comprising in forming narrow paper pulp strips and leading the

damp fiber strips through a folding device in such manner that they are longitudinally 10 folded in a straight line.

FRIEDRICH PAUL PRIEM.
